(57) **CLAIM**

What is claimed is an ornamental design for a portable
external defibrillator, as shown and described herein.

DESCRIPTION

FIG. 1 is a front perspective view of a portable external
defibrillator, showing our new design, with the top lid in
closed position;

FIG. 2 is a front view thereof;

FIG. 3 is a side view thereof;

FIG. 4 is a back view thereof;

FIG. 5 is a top view thereof;

FIG. 6 is a bottom view thereof; and,

FIG. 7 is a front view thereof, with the top lid in open
position.

The broken lines presented in the the figures is for illustrative
purposes only and forms no part of the claimed ornamental
design as shown and described herein.
